UNITED STATES PATENT OFFICE.

WILLIAM F. BATH, OF MURRAY, IDAHO.

SWITCHING DEVICE FOR ALL RAILWAYS.

No. 908,379.

Specification of Letters Patent. Patented Dec. 29, 1908.

Application filed September 19, 1905. Serial No. 279,187.

To all whom it may concern:

Be it known that I, WILLIAM F. BATH, a citizen of the United States, residing at Murray, in the county of Shoshone and State 5 of Idaho, have invented certain new and useful Improvements in Switching Devices for All Railways; and I do hereby declare the following to be a full, clear, and exact description of the same, such as will enable 10 others skilled in the art to which it appertains to make and use the same.

My present invention relates to certain improvements in switching devices to be used on all kinds of railways where switches 15 are employed.

By the employment of my invention I am enabled to throw the switch in either direction either by hand, compressed air, electricity, water power, gasoline or any other 20 suitable motive power.

Another advantage of my invention lies in the fact that I am enabled to operate the switch from the moving train without the aid of a switch man or other help.

25 In operating my switch I have brought into play a novel mechanism which securely locks the switch in the desired position and guards against it being accidentally displaced by the jarring of the moving train. 30 I have also provided means whereby an automatic signal is exhibited to the engineer showing that the switch has been operated as desired. This latter function manifestly guards against accidents that would occur by 35 the slightest break in the connecting parts, as the signal is not given until the switch has been either opened or closed.

Other objects and advantages of the invention will appear in the following specification and the novel features thereof will be particularly set forth in the appended claims.

I am enabled to accomplish the objects of my invention by the means illustrated in the accompanying drawings, in which:—

45 Figure 1 is a plan view of the track and switch of an ordinary railway showing the immediate connection between the switch and the operating rod. Fig. 2 is an elevation of the locking mechanism employed in 50 connection with the switch. Fig. 3 is an elevation showing the method of operating the switch and connected signals by means of electricity. Fig. 4 is an elevation of the mechanism employed in the locomotive for 55 conducting an electric current to the switch mechanism. Fig. 5 is a diagram on a larger scale than Fig. 2 showing more in detail the electric circuits and connections.

Referring now to the above views by numeral 1 represents the rails of the main line while 2 indicates the movable rails of the switch. The cross bar 3 connecting the movable rails 2 is pivoted to a pitman rod 4 the opposite end of which is connected to the bell crank 5, the latter being connected to 65 the pivoted lever 6 by means of the small pitman rod 7. This pivoted lever 6 is operated by means of the long traveling rod 8 which is operated by means of any one of the motive powers above numerated. This rod 70 8 can be led along to any number of switches or its motion transferred across the main line through the connecting rod or rods 9. Now it will be readily seen from the description so far gone into that movement of this 75 rod 8 in either direction will operate the switch correspondingly.

Now in regard to the locking mechanism for the switch I have provided the pivoted member 10 which operates on the same pivot 80 as that of lever 6. The outer free end of the lever 6 is provided with a pin which projects into a slot 11 in the member 10. Now assuming that this member 10 is connected to the traveling rod 8 it will be readily seen 85 that the member 10 will have considerable independent play before the terminals of the slot 11 engage the projecting pin on the lever 6. This independent play I utilize to draw the bolt 12 from the switch bar 3 after which 90 further movement of the rod 8 will operate the switch. This action of the bolt 12 is accomplished by forming the outer edge of the member 10 in the nature of a cam against which a small roller 13 on the pivoted lever 95 14 rolls. Now assuming that the parts are in the relative positions shown in Fig. 2 it will be readily seen that as the rod 8 is moved in the direction indicated by the arrow the roller 13 will be forced upward on 100 to the highest place of the cam and in so doing draws the bolt 12 from the bar 3 after which further movement of the rod 8 will open the switch. Now just as the switch is sprung the roller 13 will drop into the depression at the opposite extremity of the cam thereby permitting the spring pressed bolt 12 to engage the bar 3 and again lock it. Movement of the rod 8 in the opposite direction will evidently unlock the bar 3 and 110 permit the switch being thrown in the opposite direction.

Now in regard to the method employed for operating the rod 8, in Fig. 3 I have shown an electric motor A the shaft of which is threaded to a nut 15 the latter being connected to the traveling rod 8 by means of the pivoted lever 16. I have wired this motor A to two guide rails B and B' in such a manner as to make it possible to operate the motor in either direction according as the current is taken from rail B or from rail B'. Now assuming that the current is led from the locomotive to the roller 17 it is evident that as this roller is operated by means of the lever 18 to come in contact with the rail B the current therefrom will pass into the motor and through the lever 16 toward the small electric switch (a). This movement of the lever 16 operates the rod 8 which in turn manipulates the switch as above described. Just as the lever 16 reaches the limit of its movement in that direction it forces the switch (a) open thereby breaking the current to the motor. But simultaneously with this breaking of the current to the motor the small switch (d) is closed causing the current to show in the light (c). This flashing of the light (c) indicates to the engineer that the switch has been operated as he desired. Now should it be desired to operate the switch in the opposite direction the roller 17 is brought in contact with the guide rail B' and the motor A operated in the manner just described. Instead of bringing the current to operate the motor A from the guide rails B and B' I may employ wires arranged in any desired position.

Referring especially to Fig. 5 in which I have shown more in detail the electric circuits and connections which are indicated in Fig. 2, 20 indicates the source of electrical energy which causes the operation of the switch-actuating motor A. This source of energy may be a battery on the locomotive, car or train, a dynamo on the same driven by steam from the locomotive, or from the mechanism of the same, or from an axle of the train, or car, or such electrical energy may be derived in a known manner from an electric conductor extending along the track, this last method being the preferable one when my switching apparatus is used with electric cars or trains. The said source 20 of electrical energy is connected by a conductor 21 with the shiftable contact or roller 17. Supposing the latter to be in the position shown in Fig. 5, the hereinbefore described electric circuit for working the motor A will be through the rail or wire B and the conductor 22 to the stationary contact piece 23, thence to the movable contact 24 which forms a part of the switch a; thence by the conductor 25 and conductor 26 to the field coils 27 of the motor A; thence by the conductor 28 and conductor 29 to the movable contact 30 which also forms a part of the switch a;

thence by the contact 31, which is stationary, and the conductor 32 leading therefrom, to the armature 33 of the motor and through the same in the direction of the arrows which are shown in full lines, from which the circuit continues by the conductor 34, movable contact 35, of the switch a, stationary contact 36, and conductor 37 to the ground at G. During such passage of the current the switch will be operated in one direction. When the switch is to be operated in the other direction, the direction of the current is reversed as to the armature of the motor so that it will pass through the latter in the direction of the arrows shown in dotted lines, the current passing in the same direction as before through the field coils 27, the current in this case passing through the parts of the switch a' in a similar manner to that already described in the case of the switch a, and finally going to ground at G'. It will be understood that during the first described movement of the current and operation of the device, the switch a will be closed until the pivoted lever 16 which operates the switch mechanism has nearly completed its movement, but the switch a will be thrown open and the current interrupted and the motor A stopped, as already described at the proper time relative to the completion of the movement of the switch—that is to say, at or shortly before the time when the switch has been completely thrown.

While the above described operation is continuing, through the closed switch a, the switch a' will be open. It is also manifest that instead of employing the electric mechanism shown I may operate the rod 8 by means of compressed air, a hydraulic cylinder or by any other suitable motive power. Although I have specified that the device is particularly applicable for use on locomotives still I am aware that it can be employed to operate switches of street railways or in fact on any railway where switches are employed.

Fig. 5 is intended to show the position of the parts assumed just after the circuits have been closed through B' and the switch or circuit closer a' so as to move rod 8 to the right, which will throw and hold the switch rails open in the position shown in Fig. 1; the circuit through circuit closer a' being broken, so as to stop the operation of the motor, just after rod 8 has fully thrown the switch. Then if it be desired to throw rod 8 to the left so as to close the switch, the circuit is closed through B and a as described, whereupon motor 33 will actuate lever 16 and throw rod 8 to the left until lever 16 throws circuit closer a open, and closes switch d; at which time circuit closer a' will have been automatically closed and ready for operation to again throw the switch open; and the right-hand light switch will also be opened.

Having thus fully described my invention,

what I claim and desire to secure by Letters Patent is:—

1. In a switch operating mechanism the combination of the track and switch rails, a bar connected with the switch rails, an oscillating lever, connections between said lever and bar, a locking device adapted to engage said bar at a point between the lever connection and the switch rails to lock the switch in open or closed position; a movable member 10 beside the lever and pivoted on the lever fulcrum and connected with the lever so as to have a limited play relative thereto, means for actuating said member to cause the lever to open or close the switch, and devices operated by said movable member in its initial movement in either direction to cause said locking device to release the bar before the switch is moved and to reengage the bar 15 after the switch has been fully thrown, substantially as described. 75
2. In a switch operating device the combination of the main and switch rails, a bar connected with the switch rails, and locking 20 devices for said bar; a movable member, and means operated by said member to cause said locking device to disengage said bar on the initial movement of said member in either direction, and to reengage the bar 25 during the final movement of said member; with a lever pivoted beside and upon the fulcrum of said member and having a loose connection with one arm of the lever whereby said lever is actuated by said movable member after the locking device is released, connections 30 between the other arm of said lever and the said switch bar; and mechanism for shifting said movable member to throw the switch, substantially as described. 80
3. In a switch operating device the combination of the main and switch rails, a bar connected to said switch rails, a locking device adapted to engage said bar and lock the switch in open or closed position, an oscillating lever, connections between one end of 35 said lever and the bar for throwing the latter, a movable member adjacent the free end of said lever and a loose connection between said member and the free end of said lever; means for operating said movable member; a lever having one end connected with said locking device, a cam on said member engaging the locking device operating lever and adapted to cause the locking device to release the switch bar before the switch is thrown and to reengage the switch bar after the switch is thrown. 100
4. In a switch operating mechanism the combination of main and switch rails, a bar 40 connected with the switch rails, an oscillating lever and connections for operating the switch bar, a locking device adapted to engage said bar to lock the switch in open or closed position; a cam member pivoted beside the lever and having a limited swing 45 relative thereto, a traveling bar and connections for swinging said pivoted member to open or close the switch, and devices connected with the locking device and operated by the pivoted cam member in its initial movement in either direction to cause the locking device to release the bar and to reengage the same after the switch has been fully thrown, substantially as described. 70
5. In a switch operating device the combination of the main and switch rails, a bar connected to said switch rails, a bolt adapted to engage said bar and lock the switch in open or closed position, an oscillating lever, 50 connections between one end of said lever and the bar for throwing the latter, a pivoted member adjacent the free end of said lever and a loose pin and slot connection between said pivoted member and the free end of said lever, a traveling rod and connections for 55 operating said pivoted member, a lever having one end connected with said locking device, and a cam on said pivoted member engaging the latter lever and adapted to cause the latter to release the switch bar before the 60 switch is thrown and to reengage the switch bar after the switch is thrown. 85
6. In a railway switch controlling apparatus the combination of main and switch rails, a lever and connections for operating 65 the switch; an electric motor and mechanism actuated thereby for operating said lever to throw the switch in either direction, electric circuit closers or switches at opposite sides of said lever, electrical conductors parallel with the main line, electrical connections between the respective conductors and the respective closers, a source of electrical energy, and means on the engine or car for directing current from the source of electrical 70 energy to either of said conductors and thus through the connected circuit closers to the motor and drive its armature forward or backward, whereby the switch may be opened or closed, substantially as described. 100
7. In combination with a railway track switch, a switch operating device, a lever for operating said device, a motor and mechanism operated thereby for operating said lever in both directions; conductors parallel with 75 the main line, electric circuit closers on opposite sides of said lever, electrical connections between said closers and the respective conductors, and electrical connections between said closers and the motor; a source of electrical energy, and means on the car for transmitting current from said source to either conductor so as to drive the motor armature in either direction desired and thus open or close the track switch. 115
8. In combination with a railway track switch, a lever for operating said switch, a motor and connections for operating said lever; conductors parallel with the main line, electric circuit closers or switches on oppo- 120
- 65
- 125
- 130

site sides of said lever, electrical connections between said closers and the respective conductors, and electrical connections between said closers and the motor; a source of electrical energy, means on the car for transmitting current from said source to either conductor so as to drive the motor in either direction desired and thus open or close the switch; signals adjacent the track, electrical connections between said signals and conductors, and electric switches in said signal circuits adapted to be closed by the said lever when the latter is shifted.

9. In a railway switch controlling apparatus the combination of main and switch rails, a movable member for operating the track switch, an electric motor and mechanism actuated thereby for operating said member to throw the switch in either direction, electric circuit closers or switches at opposite sides of said member, electrical conductors parallel with the main line, electrical connections between the respective conductors and the respective circuit closers, a source of electrical energy; means mounted on the engine or car for directing the current from the source of electrical energy to either of said conductors and thus through the connected circuit closers to the motor so as to drive the motor armature in either direction whereby the switch may be opened or closed, and means for breaking the circuit after the switch is thrown, substantially as described.

10. In combination with a railway switch, a switch operating device, a movable member for operating said device, a motor and connections for operating said member, conductors parallel with the main line, electric circuit closers or switches on opposite sides of said member, electrical connections be-

tween said closers and the respective conductors, and electrical connections between said closers and the motor, a source of electrical energy, means on the car for transmitting current from said source to either conductor so as to drive the motor in either direction desired and thus open or close the switch; electric signal circuits, and signal circuit switches on opposite sides of said member adapted to be closed thereby, substantially as described.

11. In combination with main and switch rails, a switch operating device, a lever for operating said device, a motor and connections for operating said lever, conductors parallel with the main line, electric circuit closers or switches on opposite sides of said lever, electrical connections between said closers and the respective conductors, electrical connections between said closers and the motor; a source of electrical energy, means on the car for transmitting current from said source to either conductor so as to drive the motor in either direction desired and thus open or close the switch, said lever opening the circuit closer and breaking the circuit after the switch is thrown; signals adjacent the track, electrical connections between said signals and the conductors, and switches in the signal circuits and on opposite sides of said lever and adapted to be closed by the said lever when the latter is shifted so that the signals will indicate the position of the switch.

In testimony whereof, I have signed my name to this specification in the presence of two subscribing witnesses.

WILLIAM F. BATH.
